UNITED STATES PATENT OFFICE.

JESSE STEELE, OF ROANOKE, VIRGINIA.

RAILWAY FLAGGING-CANISTER.

1,317,994.

Specification of Letters Patent.

Patented Oct. 7, 1919.

Application filed December 5, 1918. Serial No. 265,427.

To all whom it may concern:

Be it known that I, JESSE STEELE, a citizen of the United States, residing at Roanoke, in the county of Roanoke and State of Virginia, have invented certain new and useful Improvements in Railway Flagging-Canisters, of which the following is a specification.

My invention relates to railway flagging canisters or boxes.

The object of the invention is to provide a compact receptacle for day signals and other railway appliances used in flagging trains and also to be in itself a night signal or marker for the rear ends of trains.

Further objects and advantages will be more fully described herein and specifically pointed out in the claims recourse being had to the accompanying drawing forming a part of this specification in which:

Figure 1 is a front view of the canister or box with the cover open and depending therefrom.

Fig. 2 is a front elevation when the cover is closed.

Fig. 3 is a rear elevation.

Fig. 4 is a cross section of the canister taken near the left hand end of Fig. 1 with the cover open.

Fig. 5 is an enlarged side elevation of one of the straps or hangers for mounting the canister.

Fig. 6 is a plan of one of the flag or fuse holders or clips.

Fig. 7 is a side view of the same.

Fig. 8 is an end view of a passenger car and its vestibule frame.

Fig. 9 is a fragmentary rear view of the canister and one of its holders or straps engaged with the diagonal members of a folding gate at the rear end of a passenger car.

Fig. 10 is a fragmentary cross section of the box and its cover showing the flange for rendering it water tight.

Fig. 11 is a similar view with the cover detached or partly open.

Fig. 12 is a side elevation of a part of the canister straps or hangers showing an anti-friction modification.

Fig. 13 is a rear elevation of the same and Fig. 14 is a fragmentary plan of the canister showing the back or suspension bar.

In the drawings like reference numerals indicate similar parts in all the several views.

1 is the sheet metal box or canister which, for compactness is usually about two or three inches thick and seven or eight inches wide and of any convenient length. 60

2 is the cover hinged to the box at 3.

The canister is provided with a handle 4 for convenience in transporting the same to and from trains.

The cover is provided with suitable 65 catches 5 and 6, Fig. 1, or they may be placed upon the box at 6 in order to secure the cover in a closed position.

Near one end of the box there is placed a partition or partitions 7 provided with suitably positioned holes 8 for the points 9 of the fuses or red fire signals 9^a, Fig. 1, also holes 11 for the pole 12 of the signal flags 13. 70

10 and 14 are clips or spring holders for 75 the fuses and flags, respectively, for supporting the ends opposite to that of the partition.

The clips are fastened to the bottom of the box by rivets or solder and are positioned 80 to suit requirements.

The interior of the canister can be fitted with receptacles for various articles at will, for instance, the box 15, Fig. 1, may be used for the lamp cord 16 for attachment to a 85 source of electricity for illuminating the interior lamp, as will be described hereafter.

In like manner, the clips 17, socket 18 and the various shaped boxes or holders 19 may be added to suit the article to be placed and held within the canister such as torpedoes, 90 marker brackets and the like.

20^a, Fig. 1, are lamp wires leading from the attachment plug 21 to the lamp socket 20 for a suitable incandescent lamp placed 95 in the box at equal distance from both ends.

When the box is closed, the red glass disk or lens 22, inserted in a circular opening in the cover 2, comes in line with the lamp or opposite each other, and forms a marker at 100

night when hung on the gate of the rear car.

In the day time, the box being usually painted yellow, acts also as a marker.

5 23 is a circular flange for holding the glass disk 22 in place over the circular perforation in the cover 2, as shown.

4 is a staple or handle for opening the canister by pulling the cover outward.

10 The cover is also provided with suitable name plates 25 or other railway marks.

Along the length of the back of the canister there is placed a flat bar or rod 26 arranged a small distance from the surface 15 by means of its bent ends and secured in place by the rivets or screws 27.

Along the bar 26 the brackets or hangers 28 are slidably mounted as indicated by the dotted lines in Fig. 3.

20 The brackets, at their upper portions, are arranged in steps 29, Fig. 5, in order to adapt the canister to varying thicknesses of the parts to which it is to be attached.

When in position for use the hangers 25 therefore adjust themselves to any point of attachment.

The lower end of the stepped portion is provided with a hook or arch 30 which acts as a snap or spring to secure the hinged

30 member to be described hereafter.

The upper part of the first step is bent downward at its position nearest the canister to form a U or bend 31, the opening at the upper part, being riveted to a filler plate 32 leaving a space for the slidable mounting of the bracket or hanger on the bar 26.

40 Figs. 12 and 13 show a modified form of bracket wherein a flanged roller 33 supported on a pin 34 is used in place of the filler plate 32, in Fig. 5, in order to diminish friction.

35 is a vertical back bar attached at its upper end to the U shaped member 31 its 15 lower end terminating in a hinged joint 35^a for the lock bar 36 which engages by a spring fit upon the hook arch 30 thereby locking the hanger upon the back bar 26.

The dotted lines 37 in Fig. 3 represent 50 the various positions of the brackets along the bar 26 in order to adjust them when hanging the canister on a car.

38 and 38^a show the end of a passenger car and its vestibule frame, respectively, and 55 shows the canister in position upon the members 39 of the folding gate with which the cars are usually equipped and the manner of its suspension can be readily seen when viewed from the platform of the car by 60 having recourse to the fragmentary view shown in Fig. 9 which indicates the manner in which the brackets or hangers 28 are attached to the crossed gate members 39.

Where the ordinary gate is used the 65 hangers are placed on the top rail and ad-

just themselves to any kind of supporting means. 40 is a lamp cord leading from the receptacle in the car ceiling to the socket 21, Fig. 1, of the canister.

41, Figs. 10 and 11, represents a narrow 70 offset flange placed around the front edge of the canister into which fits the edge of the cover 2 to render the canister water tight.

The flange may be both upon the box, as 75 at 41 or upon the cover 2 at 42 in Fig. 10, as desired.

My invention can be placed upon any passenger coach, Pullman or private car as well as upon express and other cars and in the 80 case of private or observation cars, being on the rear of the train, it is not necessary to get on the observation end of the platform to secure desired articles to be used in flagging but these can be taken from the 85 canister while standing on the ground and replaced without inconvenience to passengers.

The canister is usually made of such shape and size to adapt it to be placed in the 90 lockers at different terminals and when wanted for use the canister may be put in position on the train, with all that is desired within the same.

In this manner the articles needed may be 95 procured quickly and always found in their proper place and not exposed to the weather or to meddlesome persons.

In cases where the train has to stop in a tunnel in the day-time and where there is 100 not space enough between the train and the tunnel to reach and light the usual oil markers, my device is very desirable as it may be lighted instantaneously and have a red light or marker to protect the train. 105

I claim:

1. A railway flagging canister comprising 110 a partitioned box having a series of holders, receptacles and pockets therein, a lamp in said box, an opening in the box cover having a colored glass lens or disk therein adapted to emit light therethrough when the cover is closed, and slidable adjustable means for hanging or positioning said canister or box.

2. A flagging canister or box having compartments and securing means within the same, lamp means in the box, a cover having a colored glass disk or lens adapted to come in line with said lamp for showing 120 a night signal therethrough, a rod or bar at the back portion of said box, and brackets or hangers slidably and adjustably mounted upon the rod for positioning said canister.

3. A flagging canister or box having a 125 lamp within the same and a cover therefor having a colored glass disk adapted to come in line therewith for showing a light signal, a bar along the length of the canister and at the back portion thereof, and slidable 130

stepped locking brackets or hangers adapted to support the box upon a railway car.

4. A flagging canister having a lamp within, a hinged cover adapted to place a lens over the lamp when the cover is closed to form a red signal for the rear of a train, a bar or rod on the back of the canister and along the length thereof, and two or more slidable stepped and locking brackets

or hangers for the canister adapted to position the same to any fixed point on the car.

In testimony whereof I have hereunto affixed my signature in the presence of two witnesses.

JESSE STEELE.
